CLAIM

The ornamental design for an airport runway guard light, as shown and described.

DESCRIPTION

FIG. 1 is a perspective view of an airport runway guard light showing our new design;

FIG. 2 is a front elevational view thereof;

FIG. 3 is a side elevational view thereof, the other side being a mirror image thereof;

FIG. 4 is a rear elevational view thereof;

FIG. 5 is a top plan view thereof; and,

FIG. 6 is a bottom plan view thereof.

The broken line showing of the adjustment holes, support bracket and base member in FIGS. 1-6 is for illustrative purposes only and forms no part of the claimed design.
